UNITED STATES PATENT OFFICE.

NICOLAS F. EGLER, OF CHICAGO, ILLINOIS, ASSIGNOR, BY MESNE ASSIGNMENTS, TO THE UNION TRUST COMPANY, TRUSTEE, OF CLEVELAND, OHIO.

BILLET-HEATING FURNACE.

Application filed April 21, 1921. Serial No. 463,138.

To all whom it may concern:

Be it known that I, NICOLAS F. EGLER, a citizen of the United States, residing at % Blair Engineering Company, 343 S. Dearborn St., Chicago, in the county of Cook and State of Illinois, have invented a new and useful Improvement in Billet-Heating Furnaces, of which the following is a specification.

10. This invention relates to furnaces of the recuperative type for heating billets and the like and is fully described in the following specification and shown in the accompanying drawings, in which:

15. Figure 1 is a vertical section on the line 1— of Fig. 3, through the end of the furnace to which the billets are fed;

20. Fig. 2 is a continuation of Fig. 1 on the line 2— of Fig. 4, showing the opposite or hearth end of the furnace;

Figs. 3 and 4 are horizontal sections on the line 3—3 of Figs. 1 and 4—4 of Fig. 2 respectively;

25. Fig. 5 is a vertical section on the line 5—5 of Fig. 3, and

Fig. 6 is a vertical section on the line 6—6 of Fig. 2.

The invention is embodied in a furnace of the continuous heating type consisting of a 30 long horizontal heating passage 10 to which gas is fed through the gas main 11 and mixed with air from the air passages 12 in the mixing passages 13 where it is ignited. The flame spreads over the hearth 14 and part 35 way down the passage 10, the burned gases passing out the flue 15 to a stack (not shown).

Parallel skids, of which two are shown, consisting of water cooled pipes 16, run the entire length of the furnace and are sharply inclined at 16° at the front end. These 40 skids are supported on columns 17 as shown in Fig. 5. The billets 18 to be heated are placed side by side crosswise of these skids and as each is forced through the rear door 19 the ones in front are advanced the width of one billet until the foremost is forced down the incline 16° and out through the hinged door 20 upon the cross conveyer 21 which may be of any suitable kind.

50. Each air passage 12 has a valve 22 hingedly mounted therein upon a shaft 22a which carries a counterweight 23 and an arm 24 to which is attached a chain 25. An air pipe 26

connects at one end with the passages 12 and at the other through the heater tubes 27 and 55 the return bends 27b with the cold air manifold 28. This pipe is connected to a blower or the like (not shown). The recuperator tubes 27 are round at the ends and are rotatably mounted in the side walls of the furnace 60 as shown in Fig. 3. The central portions 27a are preferably flattened and lie across the furnace chamber near its top and above the space through which the billets 18 pass.

The method of operation is as follows:— 65

Billets are brought up to the rear door of the furnace on the skids 29 as shown in Fig. 1, the door 19 is opened and the billets forced one at a time through the rear opening. The door is then closed. At the same time, combustible gas is fed into the furnace through the passage 11 and air through the passage 12, the amount of air being regulated by means of the valves 22. The flame extends above and below the billets, the hottest part 75 of the flame coming into contact with the hottest billets. By the time the hot gases have reached the recuperator tubes 27, the flames have about ceased and the cold billets and the pipes 27 filled with cold air rapidly 80 cool the gases so that they have lost a large part of their sensible heat by the time they reach the flue 15. If desired, the tubes 27 may be turned in their bearings to deflect the hot gas down upon the billets. 85

This construction permits the furnace to be built almost entirely above ground and completely does away with the brick work so commonly used in such furnaces which is so expensive to install and to keep in repair. 90 By placing steel tubes at or near the point where the flame stops, the life of the metal tubes is greatly increased. This is largely due to the fact that sulphur is often present in the gas and when the recuperator tubes are 95 placed at too cool a point, rapid deterioration of the tubes takes place because of the acid character of the gas.

While I have shown and described but a single embodiment of my invention, it is to 100 be understood that it is capable of many modifications. Changes, therefore, in the construction and arrangement may be made without departing from the spirit and scope of the invention as disclosed in the appended 105 claims, in which it is my intention to claim

all novelty inherent in my invention as broadly as possible in view of the prior art.

What I claim as new and desire to secure by Letters Patent is:

- 5 1. A recuperative furnace comprising an elongated combustion chamber and pipes lying across said chamber through which air passes for preheating said air for the furnace.
- 10 2. A recuperative furnace comprising an elongated combustion chamber and pipes lying across the upper part of said chamber through which air passes for preheating said air for the furnace.
- 15 3. A recuperative furnace comprising an elongated combustion chamber and pipes lying across said chamber for preheating air for said furnace, said pipes having flat portions lying within the chamber and round ends mounted in the furnace walls, whereby they may be turned to any desired angle.
- 20 4. A recuperative furnace comprising an elongated combustion chamber and pipes lying across said chamber for preheating air for said furnace, said pipes having flat portions lying within the chamber and ends

journalled in the furnace walls, whereby they may be turned to any desired angle.

5. A recuperative furnace comprising an elongated combustion chamber and pipes 30 lying across said chamber for carrying air, said pipes being located near a point where the flame ceases for preheating said air for the furnace.

6. In a recuperating furnace, an elongated 35 combustion chamber, air pipes lying across said chamber near the out end of the furnace, and headers connecting the ends of said pipes, one of said headers leading to the in end of the furnace whereby the air is 40 preheated.

7. In a recuperative furnace, an elongated 45 combustion chamber, air pipes lying across said chamber near the out end of the furnace, and headers connecting the ends of said pipes, said pipes having flattened portions and being mounted to rotate about a longitudinal axis, one of said headers leading to the in end of the furnace whereby the air is preheated.

NICOLAS F. EGLER.
